MOISE FILION, OF ST. JEAN PORT-JOLI, QUEBEC, CANADA, ASSIGNOR TO THE
CANADIAN RAILWAY GATE MANUFACTURING COMPANY, OF ST. JEAN PORT-
JOLI, QUEBEC, CANADA.

CATTLE-GUARD.

1,110,915.

Specification of Letters Patent. Patented Sept. 15, 1914.

Application filed May 29, 1914. Serial No. 841,955.

To all whom it may concern:

Be it known that I, MOISE FILION, a citizen of the Dominion of Canada, and resident of St. Jean Port-Joli, in the Province of Quebec and Dominion of Canada, have invented new and useful Improvements in Cattle-Guards, of which the following is a full, clear, and exact description.

This invention relates to improvements in cattle guards, and the object is to provide a strong and durable guard which in its normal position leaves the railway line open for the passage of trains, but operates automatically to block the railway line when a person or animal attempts to pass from the railway crossing on to the railway line.

A further object is to provide a guard which if it should stick in elevated position may be depressed by a train passing in either direction without damage to the guard.

To accomplish the above objects, I provide on either side of the railway crossing pivoted platforms and pivoted barriers connected together by a link mechanism and provided with springs normally holding the barriers in depressed position and the platforms in slightly elevated position, this link and spring mechanism being such that the barriers may be swung to depressed position in either direction.

In the drawings which illustrate the invention:—Figure 1 is a half plan view of the device. Fig. 2 is a sectional view showing the method of mounting the barrier shaft. Fig. 3 is a sectional view on the line 3—3, Fig. 1. Fig. 4 is a perspective view of one of the barrier members. Fig. 5 is a perspective view of the operating spring. Fig. 6 is a perspective view of one of the plat-
40 form elevating springs.

Referring more particularly to the drawings, 11 designates the rails of a track which, adjacent the guard, are mounted on stringers 12 carried on sunken ties 13. These ties 45 are longer than usual so as to project a considerable distance beyond the track at each side and form a foundation for the guard, and permit all working parts to be inserted below the rail base.

50 At each side of the railway crossing 14, platforms or tread plates 15 are provided between and on each side of the rails, and are pivoted at the ends adjacent the crossing

on a transverse shaft 16, the opposite end being left free. A suitable distance beyond 55 the free ends of the plates 15, transverse shafts 17 are provided carrying rigidly mounted guards or barriers composed preferably of bars 18. These bars may be of any suitable material, but it is preferred to make 60 same of angle section. The section of the barrier between the rails may be formed with the angles doubled at the sides and center as shown, and the side sections of the barrier formed with only the angles adjacent the rails doubled or in any other suitable way. The ends of these angles are connected at the ends mounted on the shaft by transverse members 19, and again intermediate their ends by transverse members 20. 65 Diagonal braces 21 are also provided to stiffen the structure. Adjacent the sides of each section, short intermediate bars 22 are provided extending between the transverse members 19 and 20. Suitably shaped links 70 23 are pivoted between the bars 22 and adjacent bars 18, and extend beyond the shaft 17 slightly under the free ends of the tread plates 15, to which they are connected by suitably shaped links 24 pivoted to ears 25 75 mounted on the undersides of the plates. It will thus be seen that each section of the barrier is independently connected to the adjacent tread plate. If the shaft 17 is continuous from one side of the barrier to the 80 other, any of the tread plates will operate all three sections of the barrier on the same side of the crossing as itself, but if the shaft 17 is divided according to the number of sections in the barrier each tread plate will 85 operate only the adjacent section of barrier. This feature may be arranged as circumstances require. The center arm of the center barrier section is provided with a pair of arms 26 and 26^a extending on the opposite 90 side of the shaft from the arm and arranged at an angle of approximately 90° to one another. The arm 26 is connected by a chain 27 with one member 28 of a spring carrier. The other member 29 of the spring carrier 95 is pivotally connected to the shaft 16 or to other suitable anchorage, and is slidably arranged with respect to the member 28. Each of these members is provided with an enlarged head 30, the heads holding between 100 them a helical spring 31. The arm 26^a is

105

bifurcated and holds between the branches thereof a roller or other transverse member 32.

Tread plate cushions or elevators 33 are secured to one of the cross ties under the free corners of the tread plates. The purpose of these is to insure the rise of the platform as soon as a person or animal steps off the same, so that the weight of the platforms and the lifting of same is not thrown entirely on the barrier operating spring 31. These elevators each consist of a framework 34 bolted or spiked to the tie, and containing a suitably mounted helical spring 35 which is normally just clear of the tread plate when the same is in elevated position.

The operation of the device is extremely simple. In normal position, the parts are as shown in full lines, Fig. 3. When sufficient downward pressure is exerted on the tread plates 15, as for example, by a person or animal stepping from the crossing 14 on to them, one of the tread plates is depressed to horizontal position, and acting through the links 24 and 23 raises the barrier to the vertical position shown in dotted lines, the link 23 being fulcrumed across the shaft 17 and acting as a lever or extension of the barrier. When the barrier rises to vertical position, the lever arm 26 on the central section thereof pulls on the chain and moves the members of the spring carrier, so that the heads 30 approach one another and compress the spring 31. The elevator springs 35 under the platforms are also compressed. When the load is removed from the tread plates the elevator springs raise the same to normal inclined position, and the expansion of the springs 31 draws the barrier down to normal position. If the barriers should become stuck in elevated position by accumulations of snow or the like or for any other reason be elevated when a train passes the crossing, the barrier will not be injured. If the train strikes the barrier from the upper side, the same will depress in the ordinary manner, but if the train strikes the barrier from the under side, the same will be depressed to the position shown in dot and dash lines, Fig. 3, the links 23 and 24 moving to the position shown. In this position, the chain 27 will be bent over the roller 32 of the bifurcated arm 26^a, so that when the train has passed, the arm 26^a will receive the pull of the chain and give the spring leverage over the barrier to return the same to normal position. This arm also keeps the spring carrier and chain suitably depressed and clear of the tread plates.

Having thus described my invention, what I claim is:—

1. The combination with a railway track and crossing of tread plates pivoted at their ends adjacent the crossing, barriers pivoted adjacent the free ends of the tread plates, links pivotally connected to the barriers, links pivotally connected to the tread plates and to the barrier links, a lever arm carried by the barrier, a telescopic spring carrier fixedly mounted at one end and connected at the other end to the barrier lever, and means for returning the tread plates to normal position independently of the barrier spring. 75

2. The combination with a railway track and crossing of tread plates pivoted at their ends adjacent said crossing, a transverse shaft adjacent the free ends of said tread plates, bars of angle section rigidly connected at right angles to said shaft and forming a barrier, said bars being doubled at each side of the rails and midway between the rails to form bars of T section, 85 transverse tie members connecting the bars adjacent the shaft and intermediate the ends, diagonal braces, short bars secured between said transverse bars adjacent the sides of the barrier sections, links pivotally connected between 90 said short bars and adjacent long bars, links pivoted to the tread plates and to the extremities of said barrier links, a spring connected between a fixed point and the barrier and arranged to maintain the same normally in depressed position, and springs arranged to maintain the tread plates normally in elevated position independently of the action of the barrier springs. 95

3. The combination with a track and crossing of tread plates pivoted at their ends adjacent the crossing, barriers pivoted adjacent the free ends of the tread plates, connecting means between said tread plates and barriers arranged to operate same in opposite directions, a pair of diverging arms carried by the barrier, a barrier operating spring fixedly mounted at one end, a flexible connection between the other end of said spring and one of the barrier arms passing 110 over the extremity of the other arm whereby the spring exerts substantially uniform leverage on the barrier through an angle of approximately 180 degrees of barrier movement. 115

In witness whereof, I have hereunto set my hand in the presence of two witnesses.

MOISE X FILION.
